Patented Sept. 13, 1960

188,833

PHYSICIAN'S EXAMINING TABLE

Edgar W. Roehm, Indianapolis, Ind., assignor to W. D. Allison Company, Indianapolis, Ind., a corporation of Indiana

Filed Apr. 6, 1959, Ser. No. 55,365

Term of patent 14 years

(Cl. D83—J)

FIG. 1

FIG. 2

FIG. 3

FIG. 4

FIG. 5

FIG. 6

FIG. 7

Fig. 1 is a front elevational view of a physician's examining table embodying my new design, the rear being conventionally plain;

Fig. 2 is a top plan view thereof;

Fig. 3 is a left side elevational view thereof;

Fig. 4 is a right side elevational view thereof;

Fig. 5 is an enlarged fragmentary perspective view of one of the drawers depicted in Fig. 4;

Fig. 6 is an enlarged front elevational view of the pulls of said drawer; and

Fig. 7 is a side elevational view thereof.

I claim:

The ornamental design for a physician's examining table, substantially as shown and described.
